WILLIAM A. DOBLE, OF SAN FRANCISCO, CALIFORNIA, ASSIGNOR TO THE PELTON WATER WHEEL COMPANY, OF SAN FRANCISCO, CALIFORNIA, A CORPORATION OF CALIFORNIA.

ADJUSTABLE WEAR-RING.

1,114,238.

Specification of Letters Patent. Patented Oct. 20, 1914.

Application filed April 14, 1913. Serial No. 780,859.

To all whom it may concern:

Be it known that I, WILLIAM A. DOBLE, a citizen of the United States, residing in the city and county of San Francisco and State 5 of California, have invented certain new and useful Improvements in Adjustable Wear-Rings, of which the following is a specification.

The present invention relates to improvements in hydraulic motor, pump, or turbine construction, and more particularly to an adjustable wear ring interposed between the runner and the casing, and the invention has for its principal objects to provide an adjustable wear ring of the type mentioned, which, when worn may be adjusted to maintain a substantially fluid tight joint between the runner and the interior of the casing; to provide a wear ring the proper adjustment of which will properly position the runner relative to the inlet, to maintain equal pressures on both sides of the runner; and to provide an adjustable wear ring, the parts of which, when worn, may be readily removed from either the casing or the runner and replaced, without requiring the renewal of the runner or a section of the casing, which is necessary in devices of this type as at present constructed.

With the above mentioned and other objects in view, the invention consists in the novel construction and combination of parts hereinafter described, illustrated in the accompanying drawing, and pointed out in the claims hereto appended; it being understood that various changes in the form, proportion, size and minor details of construction within the scope of the claims hereto appended may be resorted to without departing from the spirit or sacrificing any of the advantages of the invention.

To more fully comprehend the invention, reference is directed to the accompanying drawing disclosing one form of my invention and in which—

Figure 1 is a side elevation of a hydraulic motor casing disclosing the adjusting and retaining means for the wear ring secured to the inner face of the casing. Fig. 2 is a vertical central sectional view of Fig. 1, dis-

closing the wear ring mounted on the interior of the casing and the ring carried by the runner. Fig. 3 is an enlarged transverse sectional view taken on line 3—3—Fig. 1, disclosing the configuration and mounting 55 of the wear rings and the adjusting means for the ring carried by the casing. Fig. 4 is an enlarged transverse sectional view taken on line 4—4—Fig. 1 disclosing the configuration and mounting of the wear 60 rings and the means for retaining the ring carried by the casing in position.

Referring more particularly to the drawings, the reference numeral 1 designates the casing of a hydraulic motor provided with 65 the water inlet 2 and outlet 3, and rotatably mounted in said casing is a shaft 4 provided with a hub 5, to which is secured a supporting member or disk 6, to the outer peripheral edge of which is attached one side of 70 the runner 7 of any well known type, which is positioned intermediate the inlet 2 and outlet 3.

The disk 6 is provided on one face with an outwardly projecting annular flange 8 which 75 overhangs in slight frictional contact an annular flange 9, projecting inwardly from the inner surface of the casing 1, the two flanges providing a substantially fluid tight joint at one side of the runner. The runner is provided at its opposite side with the annular flange 10 which overhangs in spaced relation an outwardly projecting annular seat 11 formed in the casing 1.

Positioned in the annular seat 11 is a substantially rectangular shaped annular metallic wear ring 12, which is retained in position by the holding screws 13 which project outwardly from the rear surface thereof and extend through openings 14 in the casing 1, and are provided on their ends with nuts 15. The wear ring 12 is adjusted in its seat 11 to compensate for the wear caused by frictional contact, by the headed adjusting screw bolts 16, which are threaded 95 through the casing 1 and are provided with lock nuts 17 to retain the same in their adjusted position.

Carried on the inner periphery of the annular flange 10 is a substantially T-shaped 100

metallic wear ring 18, the supporting portion 19 of which is secured to the flange 10 by the screws 20, and the flange 21 of the head portion 22 which lies in a plane transverse to the axis of rotation of the runner 7 covers the outer face of the flange 10 with the vertically disposed outer or wear surface 23 of the head portion in slight frictional contact with the vertical parallel wear surface 24 of the adjustable wear ring 12.

It will be apparent from the above construction that upon the vertically extending parallel wear surfaces 23 and 24 becoming worn from frictional contact with each other, that the wear ring 12 may be adjusted in its seat to bring its vertically extending wear face 24 in proper relative position to the face 23 of the wear ring 10, through the medium of the adjusting screw bolts 16 and 20 by this means compensating for the unbalanced condition of the runner which would otherwise result.

By providing a structure as disclosed in the drawing, it will be observed that upon the adjustment of the ring 12 to present the vertical wear surface 24 thereof in closer contact with the surface 23 of the ring 18, after the same have become worn, that the portion A of the runner is properly balanced relative to the intake 2, and equal pressures are maintained on both sides of the runner.

While in the drawing I have shown the adjustable wear rings as applied to but one side of the runner, it is apparent and is to be understood that the same are applicable for use in connection with either or both sides of the runner and casing.

Having thus described my invention what is claimed as new and is desired to be protected by Letters Patent is:—

1. In a device of the class described, the combination with a casing provided with a fluid inlet and a fluid outlet, of a runner rotatably mounted therein, an annular wear ring carried by the runner and having a wall thereof interposed between the side of the casing and side of the runner, an annular wear ring for the casing and in coöperative relation with said first mentioned wear ring, and means for adjusting the wear surfaces of the said wear rings relative to each other comprising a threaded bolt projecting through a threaded opening in a wall of the casing and loosely engaging the outer face of the casing wear ring, and a bolt adjustable from without the casing loosely projecting through the wall of the casing and having an adjustable threaded connection with the wear ring.

2. In a device of the class described, the combination of a hollow casing having oppositely disposed walls, a rotatable shaft projecting through the casing, a runner positioned on the shaft, an inwardly project-

ing annular flange on one wall of the casing 65 concentrically arranged relative to the said shaft, an outwardly projecting annular flange on the runner of greater diameter than the flange of the casing, and adapted to overlie said flange, the casing having an 70 inwardly projecting annular flange on its opposite wall, and the runner having an auxiliary outwardly projecting annular flange of a greater diameter than the last 75 mentioned flange of the casing, and overlying the same substantially throughout the width of the same, and an annular wear plate substantially L-shaped in cross section, one flange of which being coextensive with and projecting between the auxiliary 80 flanges of the casing and runner, and the other flange of which extends parallel with the side wall of the casing and overlies the edge of the adjacent runner flange, and adjusting means engaging the last mentioned 85 flange of the L-shaped ring.

3. In a device of the class described, the combination of a hollow casing having oppositely disposed walls, a rotatable shaft projecting through the casing, a runner positioned on the shaft, a bearing on one wall of the casing for said runner, the casing having an inwardly projecting annular flange on its opposite wall, and the runner having an auxiliary outwardly projecting 90 annular flange overlying the flange of the casing, and an annular wear plate substantially L-shaped in cross section, one flange of which projects parallel with and is interposed between the auxiliary flanges of the 95 casing and runner, and the other flange of which wear plate is interposed between the edges of the runner flange and adjacent side wall of the casing, a wear ring secured to the auxiliary flange of the runner and having a face extending parallel with the side wall of the casing whereby to engage the interposed flange of the L-shaped wear plate.

4. In a device of the class described, the combination of a hollow casing having oppositely disposed walls, a rotatable shaft projecting through the casing, a runner positioned on the shaft, a bearing on one wall of the casing for the runner, the casing having an inwardly projecting annular flange on its opposite wall, and the runner having an outwardly projecting annular flange overlying the flange of the casing, and an annular wear plate substantially L-shaped 110 in cross section, one flange of which projects parallel with and is interposed between the flanges of the casing and runner, and the other flange of which wear plate is interposed between the edges of the runner flange and adjacent side wall of the casing, an auxiliary wear ring having a face parallel with 115 the last mentioned flange of the L-shaped 120

plate, and an inwardly projecting annular flange overlying the auxiliary flange of the runner and removably secured thereto, and adjustable and detachable connections between the parallel face of the L-shaped wear plate and casing, substantially as and for the purpose described.

In testimony whereof I have signed my name to this specification in the presence of two subscribing witnesses.

WILLIAM A. DOBLE.
